DESIGN FOR A HOLDING CLIP FOR A SHOE ORNAMENT OR SIMILAR ARTICLE

Basil Darrell Huff, New York, N. Y.

Application November 9, 1942, Serial No. 108,721

Term of patent 7 years

To all whom it may concern:

Be it known that I, Basil Darrell Huff, a citizen of the United States of America, residing in New York city, county of New York, and State of New York, have invented a new, original, and ornamental Design for a Holding Clip for a Shoe Ornament or Similar Article, of which the following is a specification, reference being had to the accompanying drawing, forming part thereof.

Fig. 1 is a plan view of a holding clip for a shoe ornament or similar article showing my new design.

Fig. 2 is an edge view thereof.

Fig. 3 is a rear view of Fig. 1.

I claim:

The ornamental design for a holding clip for a shoe ornament or similar article, substantially as shown.

BASIL DARRELL HUFF.
